LIGHTING FIXTURE

Edwin F. Guth, Florissant, Mo.

Application February 26, 1944, Serial No. 524,017

1 Claim. (Cl. 240—78)

1

This invention relates to lighting fixtures and more particularly to lighting fixtures for fluorescent lamps.

Among the objects of this invention are the provision of an improved lighting fixture; the provision of a lighting fixture which, through the location of the diffusing panels, is easier to maintain and to clean; the provision of a lighting fixture which is resistant to breakage in transportation; the provision of a lighting fixture of attractive appearance and the provision of a lighting fixture which is of simple construction and is inexpensive to manufacture. Other objects will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claim.

In the accompanying drawing, in which is illustrated one embodiment of the invention,

Fig. 1 is a perspective view of the invention;

Fig. 2 is an end view partially in section of Fig. 1;

Fig. 3 is a section on an enlarged scale taken along the line 3—3 in Fig. 1; and,

Fig. 4 is a perspective of the diffusing element of Fig. 1.

Similar reference characters indicate corresponding parts throughout the several views of the drawing.

Referring now to the drawing, numeral 25 represents an outer case, channel or top housing which supports the usual electrical apparatus indicated generally at 27. The case 25 has end plates or walls 29 at either end and sockets 31 to support lamps 33. The end walls 29 are joined by side walls 53. Diffusing members 35 are supported by bent-over flanges or angles 37 on the end plates or walls 29. These flanges slope downwardly toward a median line at 43. A metal channel 39 is cemented to each diffusing member 35 on one edge thereof. The diffusers 35 may be made of any suitable material such as glass or plastic, and may be treated to render them translucent to light. Brackets 41 are formed from end plates 29 by bending up the metal, which would otherwise occupy the area 43. The diffusing panels 35 are slid into position against these end brackets 41 in the installation of the fixture.

At 51 are shown angle irons at the lower ends of the flanges 37 and suitably spaced from the

2

latter, slidably to receive the lower protected edges of the diffusers 35. These form retainers for the diffusers so that the latter may not be inadvertently raised inside of the case 25 by depressing their outer edges. The outer edges may not be raised by reason of side walls 53 of the housing 25.

The end plates or walls 29 may be formed with any desired decorative stampings and/or openings indicated generally by 45 and 47. The supporting angles 37 and end brackets 41 leave a small opening 43 down the length of the fixture. This provides a small amount of direct light immediately beneath the fixture and obviates any dark line down the length of the fixture due to the channels 39.

The present fixtures are easily installed and cleaned and the diffusing panels are easily removed for cleaning. Moreover, removing the diffusing panels permits easy access to the interior of the fixture for cleaning or repair.

The metal channels 39 hold the glass diffusing panels rigid and protect them in transit and during washing, besides preventing nicking by the brackets or stops 41. Inasmuch as fluorescent light fixtures of the type disclosed are long and relatively narrow these are important factors because the diffuser panels would otherwise be subject to damage during shipping, washing or use.

Likewise the present fixtures are attractive in appearance and avoid a substantial manufacturing cost since only one edge of the diffuser 11 is bonded to metal or analogous protective material. The use of a protective channel along only one side of each diffusing panel improves the appearance of the fixture over a construction in which material is used as a binding around all the diffuser edges. In addition, it is less costly than an all-around binding.

Where the diffuser panels 35 are composed of glass, any suitable metal-to-glass cement such as a liquid porcelain may be used in cementing the channels 39.

The fixtures of the present invention may be shipped without undue breakage in transit because the diffusing panels 35 can be shipped separately from the remainder of the fixture. The panels 35 are easily removed after the fixture has been in use, for cleaning or washing them and/or the remainder of the fixture.

In view of the above, it will be seen that the several objects of the invention are achieved and other advantageous results attained.

As many changes could be made in the above constructions without departing from the scope

of the invention, it is intended that all matter contained in the above description or shown in the accompanying drawing shall be interpreted as illustrative and not in a limiting sense.

I claim:

A lighting fixture for horizontal tubular lamps comprising an elongate horizontal housing for the lamps, said housing having end walls and side walls, said end walls terminating in lower edges which start at the side walls and slope downwardly toward a median line, inside flanges on said edges, stops located at the lower ends of said

flanges and near said median line, brackets on the insides of said end walls, said brackets being spaced above said flanges and having portions located near said stops, light-diffusing panels, reinforcing channels embracing the lower edges of said diffusing panels, said panels with their reinforcing channels being insertable and removable along said flanges and into the space between said flanges and the brackets, said reinforcements being engageable with said stops.

EDWIN F. GUTH.
